TRANSPORTATION OF NATURAL GAS

Benjamin Miller, Ozone Park, N. Y., assignor to
The Chemical Foundation, Incorporated, a corporation of New York

Application May 8, 1946, Serial No. 668,094

3 Claims. (Cl. 62—175.5)

1

This invention relates to the transportation of natural gas. The primary object of the invention is a material reduction in the cost of long-distance transportation of natural-gas fuel by removing from the natural gas the non-combustible nitrogen, this removal being accomplished either in the producing field or at a convenient intermediate point in transit to the point of ultimate use as fuel.

The nitrogen content of natural gases varies over a wide range. Some contain so much nitrogen as to be substantially non-combustible; others contain but a trace. A substantial portion of the natural gas used as fuel in locations hundreds of miles from the producing wells contains of the order of 5% to 20% of nitrogen. The treatment of such gas is the particular object of this invention.

While natural gas containing 5% to 20% of nitrogen is usually a satisfactory fuel, the removal of the nitrogen will make it better, because the diluent nitrogen increases the heat lost by escape of the combustion products at a temperature higher than the ambient. Removal of the nitrogen also improves the gas from the standpoint of cost of distribution, and even more from the standpoint of cost of transportation.

Where natural gas is used as fuel, and by far the greatest portion of it is so used, the important thing is its heating value, the number of heat units released by the combustion of a unit quantity; this is usually expressed in terms of British thermal units (B. t. u.) per standard cubic foot. If a gas has a heating value of 1000 B. t. u. per standard cubic foot, and contains 10% nitrogen, then removal of the nitrogen will increase the heating value to 1111 B. t. u. per cubic foot. Nine cubic feet of the denitrogenized gas will be required for actual use as fuel to take the place of ten cubic feet of the original. Then the pipes through which the gas flows from the point at which denitrogenization is accomplished to the consuming burners can carry $\frac{1}{10}$ more fuel value in the same number of cubic feet. But more importantly the capacity of the pipes will be increased even more than $\frac{1}{10}$, because the weight of a cubic foot of methane, the principal component of natural gas, is only 57% as great as the weight of a cubic foot of nitrogen, and the carrying capacity of a long distance gas pipe-line is inversely proportional to the square root of the weight of a cubic foot of the gas flowing. A further advantage of denitrogenization is that the power required to compress the gas at each compressing station will be lower.

As a particular example there may be considered a typical natural gas from the great Hugoton field which is located in the western portions of Kansas and Oklahoma and the extreme northwestern portion of Texas. After passing through a natural gasoline plant for removal of all hydrocarbons less volatile than normal butane, a typical gas from the Hugoton field would have the following analysis:

Component:	Percent by volume
Methane	75.72
Propane	2.54
Ethane	5.83
Iso-butane	0.20
Normal butane	0.42
Nitrogen	15.29
	100.00

20 A cubic foot of gas (measured at 60 degrees Fahrenheit and 14.735 pounds per square inch absolute) having this composition would weigh 0.05220 pound, and would have a heating value of 958 B. t. u. Removal of the nitrogen would 25 leave a gas weighing only 0.04820 pound per cubic foot, having a heating value of 1131 B. t. u. per cubic foot. The capacity of a pipe-line for the denitrogenized gas would be 23% greater than its capacity for the gas before denitrogenization, on a heating value basis. This increase in capacity of 23% would be due to an increase of 18% in the heating value of each cubic foot and to an increase of over 4% in the capacity on a cubic foot basis.

30 35 The method of separation which I employ involves the liquefaction of at least a substantial portion of the natural gas. While a process involving liquefaction of gases has been used extensively to prepare oxygen from air, and a similar process has been applied for the extraction of helium from natural gas, such processes have required such costly equipment and have been so costly to operate as to discourage consideration of liquefaction of natural gas as a part of a process for removing nitrogen therefrom. But I have found that nitrogen can be removed economically from natural gas intended to be transported by pipe-line for a long distance by conducting the liquefaction and separation steps 40 under a high pressure comparable to the pressure at which the gas is to be transported, and then expanding the separated nitrogen to obtain the necessary refrigerating effect. Frequently the gas is available from the producing wells at a 45 pressure high enough for the process, but in any 50 55

case the pressure required for economical transportation by pipe-line is sufficient. In some cases the pipe-line pressure is higher than necessary for the separation process, although the pressure at which the gas is available from the wells is not so high as desired for the separation process. In such cases it is desirable to compress the gas to the separation pressure, make the separation, and then compress the denitrogenized gas to the pipe-line pressure. While the separated nitrogen is expanded to obtain the refrigerating effect, the pressure of the denitrogenized gas is conserved as fully as possible, and may even be increased in some cases.

The separation of gases by liquefaction and fractionation usually requires considerable power; such power cost is usually the greatest cost involved. However, I may not require any power for the separation, in that my system will require no more power—in some cases less power—than is required to conduct the transportation according to the method now employed. At present all of the gas must be compressed to the transportation pressure, and as it travels through the pipe line the pressure is reduced, which means that recompression is required at intervals. For example, under present practice, the gas may come out of the well at a pressure of 425 pounds per square inch, and be allowed to flow through a pipe gathering system which connects many wells to a field station; it may reach that station at a pressure of the order of 350 pounds per square inch. It is then compressed to 750 p. s. i. and put into a pipe line. After traveling 75 miles the pressure may drop to about 600 p. s. i. The gas is then compressed again to about 750 p. s. i., and fed into the next section of line. This process is repeated approximately every 75 miles, and the gas may be compressed a dozen times before it reaches its destination. In the novel system of the invention the gas would be compressed at the field station to about 450 p. s. i. It would then pass through the nitrogen removal plant and be separated into two parts—one containing most of the nitrogen, and the other containing very little nitrogen, but most of the fuel value. The nitrogen-containing portion would be expanded to atmospheric pressure, thereby deriving most of the necessary net refrigerating effect. The fuel fraction would be delivered under pressure of 250–300 p. s. i., the pressure drop being incident to recovery of the regenerated portion of the refrigerating effect. Then only this portion would have to be compressed to 750 p. s. i. for transportation. If the gas contained 20% nitrogen, only 80% of it would have to be compressed to 750 p. s. i. At each recompressing station there would be another saving in power, because the quantity of gas handled would be 20% less for a certain amount of heating effect. The pressure loss in going through the nitrogen removal plant would require power to make up, but this would be far outweighed by the savings of power at each recompressing station.

The invention will be explained with the aid of the accompanying drawing, which is a flow sheet showing a preferred modification of the process. The natural gas may be first treated for the extracting of natural gasoline, butane, and propane; although it is not necessary that these less volatile hydrocarbons be completely removed, it is desirable that the amount of easily liquefiable material be small. Hydrocarbon extraction need not be more complete than would

be practised in any event to avoid condensation in the pipe line. The extraction of natural gaso-line may be effected by any conventional method, such as scrubbing the gas with absorption oil. There remains a mixture which is designated for convenience as methane and nitrogen, although minor amounts of ethane, propane, and butane may be present, and in some cases the total percentage of hydrocarbons other than methane may exceed the percentage of nitrogen. The mixture will generally contain water, frequently contain a small amount of carbon dioxide, and occasionally contain a small amount of hydrogen sulfide. The presence of hydrogen sulfide, carbon dioxide, or water is quite undesirable, so that the first step shown on the flow sheet is their removal. The removal may be by any convenient means, such as by scrubbing the gas with a solution of an amine, followed by passing the gas through a mass of activated alumina as carried out for example in the extraction system 1.

The mixture then passes through line 3 and heat exchanger A, where it is cooled. From heat exchanger A the mixture passes through the line 4, reboiler coil 5 of the fractionator 6, and is further cooled. It then passes through line 7 and heat exchanger B, where it is further cooled, and partially liquefied. The mixture then passes through line 8, heat exchanger C and line 9, exchanger D, where it is further cooled, and more of it liquefied and thence passes into the fractionator 6 through line 10.

The fractionator is preferably a bubble tower type. At the bottom is a reboiler section 11 enclosing the reboiler coil 5; in the reboiler section liquid accumulates until it reaches the selected level. Then the liquid level controller 12 allows liquid to leave the reboiler section and pass to heat exchanger B.

Vapor from the top of the fractionator passes through line 13 and heat exchanger C where it is warmed. It then passes through line 14 to expander 15 where its pressure decreases, and it gives up mechanical energy to drive compressor 16. The expansion cools the vapor, and part of it may condense, but generally the exit pressure from expander 15 is controlled so that no condensation occurs therein. The cold vapor then passes through line 17 to reflux coil 18 where it is reheated. It then passes through line 19 and expands again in expander 20 where mechanical energy is abstracted to drive associated compressor 21. The expansion cools the vapor and again some of the vapor may condense. The cooled vapor then passes through line 22 to the reflux coil 23 located in the upper section of the fractionating column. In passing through the coil the vapor absorbs heat and the heated vapors then pass through line 24 to the heat exchanger D, thence through the line 25 to heat exchanger B and then through line 26 to heat exchanger A. In this series of heat exchanges the vapor is progressively increased in temperature and is discharged through line 27 at approximately atmospheric pressure and at a temperature slightly lower than the temperature of the mixture which enters heat exchanger A through line 3.

The liquid which accumulates in the reboiler section of the fractionator and passes through line 28 to heat exchanger B, evaporates therein under a pressure somewhat lower than the pressure in the fractionator. The vapor formed as a result of this evaporation leaves heat exchanger B through line 29 and passes through heat ex-

changer A wherein it is heated to a temperature somewhat lower than the temperature of the mixture which enters heat exchanger A, then passes through line 36, compressor 16 and compressor 21 and finally is discharged through line 31 under pressure higher than the pressure under which it was formed.

The stream leaving compressor 31 is designated on the drawing as "Methane." It will be appreciated that this stream also contains other hydrocarbons, if such were in the mixture to be separated, but will be substantially free of nitrogen. This freedom from nitrogen, as will be understood, is insured by controlling the temperature in the reboiler section 11 of the fractionator. If there are no other hydrocarbons present, the temperature in the bottom of the fractionator is not allowed to go below the boiling point of methane under the operating pressure. If other hydrocarbons are present as well, a somewhat higher temperature is maintained. The temperature in this reboiler section can be kept from being too low by several means. One preferred modification is to provide a by-pass around heat exchanger A for the methane stream. Letting all or part of the methane stream pass directly to compressor 16 from heat exchanger B decreases the cooling effect which heat exchanger A has on the incoming mixture, and thereby allows the mixture to enter the reboiler coil at a higher temperature; the higher temperature of the mixture in the boiler coil causes more heat to be transferred to the liquid in the reboiler section, thus tending to increase its temperature.

The stream discharged through line 27 is designated on the flow sheet as "Nitrogen." This stream is so designated because it contains substantially all the nitrogen which was in the incoming mixture. It also will contain any helium which the incoming mixture contained, and it may under some circumstances include a substantial fraction of methane. The ratio of nitrogen to methane in the nitrogen stream will depend upon the fraction of nitrogen in the mixture to be separated. For example, if the mixture to be separated has 20% nitrogen, the ratio of nitrogen to methane in the nitrogen stream will be high; it may be 19 to 1. If the mixture to be separated has 15% nitrogen, the ratio of nitrogen to methane in the nitrogen stream may be 9 to 1. If the mixture to be separated has only 5% nitrogen, the ratio of nitrogen to methane in the nitrogen stream may be 1 to 1, or even lower.

It will thus be seen that the greater the percentage of nitrogen in the natural gas, the greater the benefit to be obtained by removing the nitrogen. Similarly the greater the distance the gas is to be transported, the greater the benefit to be obtained by removing the nitrogen. My process is therefore adapted to be used to treat a natural gas having a relatively high nitrogen content when the distance the gas is to be transported is relatively small, while it is adapted to be used to treat natural gases having relatively low as well as relatively high nitrogen contents when the distance the gas is to be transported is relatively great.

While my process can be operated over a wider range of pressures, I prefer to operate in the range of 400 to 600 pounds per square inch, the preferred operating pressure being higher for the lower nitrogen contents.

As an example, with a mixture containing

about 15% nitrogen at operating pressure of 30 normal atmospheres, or 441 pounds per square inch absolute, is convenient. This pressure is substantially maintained on the mixture through the heat exchangers and in the fractionator; there is of course some drop in pressure as the mixture passes through the heat exchangers. The nitrogen stream leaving the fractionator passes through heat exchanger C at substantially the same pressure, and is expanded through expander 15 to a pressure in the range of 5 to 8 normal atmospheres. It passes at substantially this pressure through reflux coil 18, and then is expanded through expander 20 to a pressure in the range 1 to 2 normal atmospheres, leaving expander 20 with the pressure required to pass through reflux coil 23 and heat exchangers D, B, and A to discharge at the prevailing atmospheric pressure. The methane stream leaving the fractionator is reduced in pressure only enough so that it may evaporate in heat exchanger B—the evaporation takes place at from 250 to 270 pounds per square inch absolute. In passing through compressors 16 and 21 the pressure of the methane is increased to 275 to 300 pounds per square inch absolute.

Heat exchanger C and heat exchanger D are indicated as simple heat exchangers, in which one stream is cooled and one stream is heated. Heat exchanger A and heat exchanger B are indicated as combination heat exchangers, in which one stream is cooled, but two streams are heated. However, it is possible to combine heat exchanger C with heat exchanger D to form a combination heat exchanger, in which case the mixture being cooled would give up heat to two nitrogen streams flowing in parallel with respect to heat transfer. Also, heat exchanger A can be replaced by two simple heat exchangers, with part of the mixture flowing through one in heat transfer relation to the methane stream while the rest of the mixture flows through the other in heat transfer relation to the nitrogen stream. Similarly simple exchangers can also be substituted for heat exchanger B. The heat exchangers may be of the shell-and-tube or double-pipe type, and the combination heat exchangers, if used, may be of the double-pipe-within-shell type. Finned heat exchange surface may be used, especially in contact with the nitrogen stream.

While the fractionator is shown as having a reboiler section fitted with a reboiler coil, it is possible to use a separate reboiler in another shell. It is also possible to have one or more additional reboiler coils located below the tray on which the mixture enters the fractionator; additional coils would be placed on trays progressively upward starting with the bottom tray.

It will be appreciated that instead of reflux coils located at the top of the fractionator, it is possible to use a separate condenser in another shell, the condensate being returned to the top tray as reflux.

Reflux coil 18 is shown in the drawings as located above the top tray, and reflux coil 23 is shown located above the next-to-top tray. It is possible to interchange these locations, or if desired to locate both reflux coils above the top tray. It is also possible to have one or more additional reflux coils located above trays lower than the next-to-top tray.

Expanders 15 and 20 may be engines or turbines, but turbines are preferred. While the expanders are shown as driving compressors 16 and

21, it is possible to load the expanders in other ways.

Expansion with abstraction of mechanical energy as shown is preferred; the expansion should be as nearly isentropic as can be conveniently arranged. However, it is possible to expand without abstraction of mechanical energy, and such isenthalpic expansion will result in a lowering of temperature. It may be desirable to provide a by-pass across each expander, so that isenthalpic expansion of part or all of the nitrogen stream may be employed. This is particularly useful when starting up the process, before any liquid has accumulated in the reboiler section, and until the liquid has risen to the selected level.

When starting up the process the stream leaving the top of the fractionator will have the same composition as the incoming mixture. As the gas expands, isenthalpically, isentropically or in an intermediate manner, its temperature drops. The colder gas passes back in heat exchange relation with the incoming gas, and the temperature level decreases progressively until liquefaction starts, then more slowly until the equilibrium temperature level is reached. It is possible to shorten the starting period by the use of auxiliary refrigeration, as by cooling the incoming mixture by heat exchange with propane boiling at atmospheric pressure.

It will be understood that the fluids in the several parts of the equipment are at various temperatures. The incoming mixture will normally be at a temperature close to the prevailing atmospheric temperature, but in going through the process zones of lower temperatures are encountered, the lowest temperature being at the outlet of expander 20, where it may be of the order of -320 degrees Fahrenheit. It is therefore essential that the equipment be well insulated against heat leakage in from the ambient, and also to prevent heat exchange except where such is desired.

The nitrogen stream will usually be allowed to escape to the atmosphere, although there may be uses developed for it; however, where the methane content of the nitrogen stream is high, the nitrogen stream may be used as fuel.

It will now be appreciated that the process of the invention insures many positive economical advantages. The described denuding of the nitrogen in the gas enriches the gas with respect to its fuel value and concomitantly reduces power requirements for compression to the extent that the heavier nitrogen constituent is eliminated. This advantage is a cumulative one since such lowered power requirements are reflected at each recompression stage in the entire system. As explained, additional economies may be achieved by utilizing the expansion of the nitrogen fraction to secure at least a part of the desired refrigeration.

I claim:

1. The method of preparing, from natural gas containing a substantial fraction of nitrogen, a gaseous fuel suitable for economical long distance pipe line transportation which comprises cooling a mixture derived from said natural gas and containing nitrogen and methane under a pressure in the range of 400 to 600 pounds per square inch to a temperature at which at least a substantial portion of the methane is liquefied, separating the mixture while substantially maintaining the pressure into a liquid portion in which the ratio of methane to nitrogen is substantially greater than it is in the mixture, and a vapor portion

in which the ratio of methane to nitrogen is substantially less than it is in the mixture, evaporating the liquid in heat exchange relationship with another portion of the mixture while maintaining on the liquid a pressure not less than half of that maintained on the mixture and passing the vapor evolved by evaporation of the liquid in heat exchange relationship with another portion of the mixture while maintaining said last recited vapor under substantially the same pressure under which it was evolved, expanding the vapor in which the ratio of methane to nitrogen is substantially less than it is in the mixture under conditions which insure that the temperature of the vapor immediately after expansion is lower than the temperature of the vapor when it left the separation step, and passing the expanded vapor in heat exchange relationship with another portion of the mixture, the cooling off the mixture taking place in at least three stages of progressively lower temperature, the expanded vapor supplying the cooling effect in the lowest temperature stage and the evaporating liquid supplying at least part of the cooling effect in an intermediate temperature stage.

2. The method of preparing, from natural gas containing a substantial concentration of N₂, a gaseous fuel suitable for economical long distance pipe line transportation under substantial pressure which comprises cooling a mixture derived from said natural gas and containing nitrogen and methane while maintaining the pressure in excess of 400 pounds per square inch to liquefy at least a substantial portion of the methane, subjecting the mixture to fractionation under substantial superatmospheric pressure in the range 400-600 pounds per square inch to produce a liquid substantially free from nitrogen and a vapor containing substantially all of the nitrogen, expanding said nitrogen-containing vapor under conditions which insure that the temperature of the vapor immediately after expansion will be lower than the temperature of the vapor leaving the fractionation step, passing the expanded vapor in heat exchange relation with another portion of said nitrogen-containing vapor which has not yet been expanded to liquefy a portion thereof, utilizing the liquid formed in the last-recited step, as reflux in said fractionation step and passing the nitrogen-containing vapor separated from the reflux in heat exchanging relationship with another portion of the mixture whereby the said nitrogen-containing vapor is superheated prior to the said expansion.

3. The method of preparing, from natural gas containing a substantial concentration of N₂, a gaseous fuel suitable for economical long distance pipe line transportation under substantial pressure which comprises cooling a mixture derived from said natural gas and containing nitrogen and methane while maintaining the pressure in excess of 400 pounds per square inch to liquefy at least a substantial portion of the methane, subjecting the mixture to fractionation under substantial superatmospheric pressure in the range 400-600 pounds per square inch to produce a liquid substantially free from nitrogen and a vapor containing substantially all of the nitrogen, expanding said nitrogen-containing vapor under conditions which insure that the temperature of the vapor immediately after expansion will be lower than the temperature of the vapor leaving the fractionation step, passing the expanded vapor in heat exchange relation with another portion of said nitrogen-containing

vapor which has not yet been expanded to liquefy a portion thereof, utilizing the liquid formed in the last-recited step, as reflux in said fractionation, expanding the vapor leaving the reflux-forming step under conditions which insure that the temperature of the vapor immediately after expansion will be lower than the temperature of the vapor leaving the reflux-forming step, and passing such further expanded vapors in heat-exchanging relationship with another portion of 10 said nitrogen-containing vapor, which has not yet been expanded to liquefy a portion thereof, and utilizing the liquid formed in the last recited step as additional reflux in said fractionation step.

BENJAMIN MILLER.
